UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed December 18, 1920. Serial No. 431,746.

My present invention relates to the use of electron discharge apparatus of the well known vacuum tube type, and the application of such apparatus to various uses such as amplification of electric currents or the detection of radio signals.

An object of my invention is to provide new and improved circuit organizations for and methods of operating such apparatus which are more efficient than those heretofore employed.

The novel features which I believe to be characteristic of my invention are set forth with particularity in the appended claims. My invention itself, however, both as to its organization and method of operation together with further objects and advantages thereof will best be understood by reference to the following description taken in connection with the accompanying drawing in which Fig. 1 shows diagrammatically a circuit arrangement which may be used for the amplification of variable currents, particularly of audio frequency. Fig. 2 shows a similar circuit arrangement for the relaying or amplification of radio frequency currents, and Fig. 3 shows a circuit arrangement which may be employed as a detector of radio signals.

As indicated in the drawings, I employ an electron discharge device 1 having the usual electron emitting cathode 2, anode 3, a third or grid electrode 4, and a grid or discharge controlling electrode 5.

The direct current source 6 which is connected in the plate or anode circuit between cathode 2 and anode 3 furnishes the current for the operation of the device. By means of this source a potential may also be applied

to the grid electrode 4 which is intermediate the potential of the cathode 2 and anode 3, the desired reduction in potential being obtained by the use of a potentiometer 7. The current to be amplified is impressed upon the

grid circuit between cathode 2 and grid 5 by means of a transformer 8. The amplified current in the plate circuit, if of audio frequency, may be impressed by means of the transformer 9 upon the circuit of a tele-

phone receiver 10 for the purpose of producing an audible indication of the amplified current flowing in the plate circuit. In case the current to be amplified is not of audible frequency any other suitable form of indicating device may be associated with

the plate circuit for obtaining the desired indication of the amplified current.

In the operation of the system shown, the potentials applied to the anode 3 and grid electrode 4 may be such that the grid electrode 4 will emit secondary electrons which will be received by the more positive anode 3. When this method of operation is employed the potentials are preferably so chosen that enough secondary electrons will be emitted from the grid electrode 4 to produce a negative resistance characteristic in the circuit between cathode 2 and grid electrode 4. When operated in this way the variation in the potential of the grid 5 will produce a high amplification of the current flowing in the circuit between cathode 2 and grid 4 by reason of the negative resistance characteristic of this circuit. There will at the same time be produced a corresponding complementary change in the current in the circuit between cathode 2 and anode 3. This circuit will not possess a negative resistance characteristic over the usual operating range and therefore will be stable in its operation. In order to produce a high degree of amplification a positive resistance 18 which should preferably be approximately equal to the negative resistance in the circuit between the cathode 2 and grid electrode 4 is inserted in that circuit. I have indicated the use of a single source 6 for obtaining the potential necessary for the operation of the device, but separate sources may be employed for the application of the potentials to the two electrodes 3 and 4 in case it is not convenient to obtain the desired potentials from a single source.

In the arrangement of Fig. 2, I have indicated a source 12 of radio frequency current which is amplified by the system and applied to the transmitting antenna 13 for the transmission of radio signals.

In the arrangement of Fig. 3 I have indicated the use of an electron discharge device as a detector of radio signals. In this case the signals to be detected which are received by the antenna 14 are impressed upon the usual resonant grid circuit 15, this grid circuit being provided with the usual stopping condenser 16 and grid leak 17.

In any of the cases illustrated the device may be operated as a negative resistance device in accordance with the methods of operation described in the paper entitled

"The Dynatron" published by me in the Proceedings of the Institute of Radio Engineers for 1918 at page 5.

- In case it is not desired to employ the negative resistance characteristic of the device it may however, be employed in the same manner as the usual three-electrode device. In this case the grid electrode 4 should be maintained at a positive potential intermediate the potentials of cathode 2 and anode 3. The desired potential for the operation of the grid 4 may in this case be obtained either by means of the potentiometer 7 of Figs. 1 and 2 or by varying the resistance 18 alone as indicated in Fig. 3. In the operation of the usual three-electrode devices it has been found that there is a marked tendency for the production of undesired high frequency oscillations by reason of the capacity between the discharge controlling grid and the anode. The use of the extra grid electrode 4 between the discharge controlling grid and the anode, however, screens the two electrodes in such a way that this tendency is reduced. In this case the resistance 18 is preferably shunted by a condenser 11, which will permit the alternating component of the current flowing to grid electrode 4 to flow around the resistance 18. The capacity effect between grid and anode for a three electrode device also greatly reduces the possible amplification of the device when radio frequencies are employed. The use of the extra grid electrode 4 reduces the capacity effect in such cases and permits a high degree of amplification with radio frequencies.
- In the usual three-electrode device, a high plate impedance, which is desirable for operation, can be obtained only at the sacrifice of grid control so that in practice it has been found best to make the plate impedance between 10,000 and 100,000 ohms. The use of the extra grid electrode in the manner described, however, screens the cathode from the effect of plate voltage, thereby making it possible to have a very high plate impedance without sacrificing grid control and thereby greatly increasing the amplification.
- While I have shown and described only three circuit arrangements in which my invention is employed, it will be apparent that my invention is by no means limited to the exact form of apparatus or the precise circuit connections indicated, as many modifications, both in the apparatus used as well as in the circuit connections, may be made without departing from the scope of my invention as set forth in the appended claims.
- What I claim as new and desire to secure by Letters Patent of the United States, is,—
1. An electron discharge device comprising an electron emitting cathode and at least two other electrodes enclosed in an evacuated receptacle, and sources of potential applied

to the electrodes of said device in such a way that the potentials of the other two electrodes are positive with respect to the cathode and the device has a working range over which the current flow from cathode to the electrode nearest the cathode will vary inversely as the potential applied thereto, and the current between cathode and the electrode farthest from the cathode will vary in the opposite manner. 75

2. An electron discharge comprising an electron emitting cathode, an anode and a grid electrode which is interposed between cathode and anode, a source of potential for maintaining the anode at a positive potential 80 with respect to the cathode, and means for maintaining the grid electrode at a potential which is intermediate the potentials of cathode and anode, the potentials of the anode and grid electrode being so chosen that the current between cathode and grid electrode will, over a definite working range of potential vary inversely as the potential difference between cathode and grid. 85

3. An electron discharge device comprising 90 an electron emitting cathode, an anode and a grid electrode interposed between cathode and anode, means for impressing a constant positive potential upon said anode, means for impressing a positive potential upon the 95 grid electrode of such a value as to produce an emission of secondary electrons from said grid electrode, the potentials applied to said electrodes being of such values that the device will have a negative resistance characteristic between cathode and grid electrode. 100

4. The method of operating an electron discharge device comprising an electron emitting cathode, an anode, and a third electrode interposed between cathode and anode which consists in applying a constant positive potential to the anode and applying a positive potential to the third electrode of such a value as to produce an emission of 105 secondary electrons therefrom sufficient to 110 give the device a negative resistance characteristic.

5. The method of operating an electron discharge device comprising an electron emitting cathode, an anode and a third electrode between cathode and anode which consists in applying a constant positive potential to the anode and applying a positive potential to the third electrode of such a value as to give the device a negative resistance characteristic. 115

6. An electron discharge device comprising an electron emitting cathode, an anode and two grid electrodes enclosed in an evacuated receptacle, a source of potential for maintaining the anode at a positive potential with respect to the cathode, means for maintaining one of the grid electrodes which is interposed between cathode and anode at a potential which is intermediate 125 130

- the potentials of the cathode and anode, the potentials of the anode and grid electrode being so chosen that the current between cathode and grid electrode will, over a definite working range of potential vary inversely as the potential difference between cathode and grid electrode, and means for varying the potential of the second grid to vary the current flow between cathode and anode. 10
7. An electron discharge device comprising an electron emitting cathode, an anode and two grid electrodes interposed between cathode and anode, a source of potential for maintaining the anode at a positive potential with respect to the cathode, means for maintaining the grid electrode nearest the anode at a potential intermediate the potentials of the cathode and anode, the potentials of the anode and said grid electrode being so chosen that secondary electrons will be emitted from the grid in sufficient amount to give the device a negative resistance characteristic between cathode and said grid electrode, and means for varying the potential of the second grid to vary the current flow between cathode and anode. 15
8. The method of operating an electron discharge device having an electron emitting cathode, an anode and two grids enclosed in an evacuated receptacle; at least one of said grids being interposed between cathode and anode, which consists in maintaining the anode and grid electrode nearest the anode at such potentials with respect to the cathode that a sufficient flow of secondary electrons from grid electrode to anode will be produced to give the device a negative resistance characteristic between cathode and grid electrode, and varying the potential of the second grid electrode and thereby varying the current flow between cathode and anode. 30
9. The method of operating an electron discharge device having an electron emitting cathode, an anode and two grid electrodes interposed between cathode and anode, which consists in maintaining the anode and grid electrode nearest the anode at such potentials with respect to the cathode that the device will have a negative resistance characteristic between cathode and said grid electrode, and varying the potential of the grid electrode nearest the cathode and thereby varying the current flow between cathode and anode. 45
10. An electron discharge device comprising an electron emitting cathode, an anode, a third electrode and a discharge controlling member, of means for supplying a definite positive potential to said anode, means for supplying a lower positive potential to the third electrode of such a value as to give the device a negative resistance characteristic between cathode and third electrode, means for applying a variable potential to the discharge controlling member to vary the current between cathode and anode, and means associated with the circuit between cathode and anode for producing an indication of the current variations in that circuit. 50
11. An electron discharge device comprising an electron emitting cathode, an anode and two grid electrodes interposed between cathode and anode, of means for supplying a definite positive potential to said anode, means for supplying a lower positive potential to the grid electrode nearest the anode of such a value as to give the device a negative resistance characteristic between cathode and grid electrode, means for applying a variable potential to the grid electrode nearest the cathode to vary the current between cathode and anode, and means associated with the circuit between cathode and anode for producing an indication of the current variations in that circuit. 55
12. The method of operating an electron discharge device comprising an electron emitting cathode, an anode, a third electrode and a discharge controlling member which consists in producing an emission of secondary electrons from the third electrode sufficient to give the device a negative resistance characteristic between cathode and third electrode, applying a variable potential to the discharge controlling member to vary the current between cathode and anode and producing a desired indication of the current changes between cathode and anode. 60
13. The method of operating an electron discharge device comprising an electron emitting cathode, an anode and two grid electrodes interposed between cathode and anode, which consists in producing an emission of secondary electrons from the grid electrode nearest the anode sufficient to give the device a negative resistance characteristic between cathode and said grid electrode, applying a variable potential to the grid electrode nearest the cathode to vary the current between cathode and anode and producing a desired indication of the current changes between cathode and anode. 65
14. In a system for detecting radio signals, the combination of an electron discharge device having an electron emitting cathode, an anode, and two grid electrodes enclosed in an evacuated receptacle, a source of potential for maintaining this anode at a positive potential with respect to the cathode, means for maintaining one of the grid electrodes which is interposed between cathode and anode at a potential intermediate the potentials of the cathode and anode, the potentials of anode and grid electrode being so chosen that the current between cathode and grid electrode will, over a definite working range of potential vary inversely as the potential difference between cathode and grid electrode, means for supplying the ra- 70 75 80 85 90 95 100 105 110 115 120 125 130

5 dio signals to be detected to the second grid to vary the current flow between cathode and anode in accordance with the signals and means associated with the circuit between cathode and anode for producing a desired indication of the signaling current in that circuit.

10 15. The method of operating an electron discharge device having an electron emitting cathode, an anode and two grids enclosed in an evacuated receptacle, at least one of said grids being interposed between cathode and anode, to detect radio signals which consists in maintaining the anode and grid electrode nearest the anode at such potentials with respect to the cathode that a sufficient flow of secondary electrons from grid electrode to anode will be produced to give the device a negative resistance characteristic between cathode and grid electrode, supplying the signals to be detected to the second grid electrode and thereby varying the current flow between cathode and anode in accordance with the signals and producing a desired indication of the signaling current flowing between cathode and anode.

16. Means for amplifying variable electric currents comprising an electron discharge device having an electron emitting cathode, an anode and two grid electrodes enclosed in an evacuated receptacle, a source of potential for maintaining the anode at a positive potential with respect to the cath-

55 ode, means for maintaining one of the grid electrodes which is interposed between cathode and anode at a potential which is intermediate the potentials of the cathode and anode, the potentials of cathode and grid electrode being so chosen that the current 40 between cathode and grid electrode will, over a definite working range of potential vary inversely as the potential difference between cathode and grid electrode, a circuit between cathode and second grid and means 45 for supplying the current to be amplified to said circuit to vary the current flow between cathode and anode in accordance with the current to be amplified.

17. The method of operating an electron discharge device having an electron emitting cathode, an anode and two grid electrodes interposed between cathode and anode to amplify a variable electric current which consists in maintaining the anode and grid 55 electrode nearest the anode at such potentials with respect to the cathode that the device will have a negative resistance characteristic between cathode and said grid electrode, and supplying the current to be amplified to a circuit between the cathode and the grid electrode nearest the cathode and thereby varying the current flow between cathode and anode in accordance with the current to be amplified. 60 65

ALBERT W. HULL.

dio signals to be detected to the second grid to vary the current flow between cathode and anode in accordance with the signals and means associated with the circuit between cathode and anode for producing a desired indication of the signaling current in that circuit.

15. The method of operating an electron discharge device having an electron emitting cathode, an anode and two grids enclosed in an evacuated receptacle, at least one of said grids being interposed between cathode and anode, to detect radio signals which consists in maintaining the anode and grid electrode nearest the anode at such potentials with respect to the cathode that a sufficient flow of secondary electrons from grid electrode to anode will be produced to give the device a negative resistance characteristic between cathode and grid electrode, supplying the signals to be detected to the second grid electrode and thereby varying the current flow between cathode and anode in accordance with the signals and producing a desired indication of the signaling current flowing between cathode and anode.

16. Means for amplifying variable electric currents comprising an electron discharge device having an electron emitting cathode, an anode and two grid electrodes enclosed in an evacuated receptacle, a source of potential for maintaining the anode at a positive potential with respect to the cath-

ode, means for maintaining one of the grid electrodes which is interposed between cathode and anode at a potential which is intermediate the potentials of the cathode and anode, the potentials of cathode and grid electrode being so chosen that the current between cathode and grid electrode will, over a definite working range of potential vary inversely as the potential difference between cathode and grid electrode, a circuit between cathode and second grid and means for supplying the current to be amplified to said circuit to vary the current flow between cathode and anode in accordance with the current to be amplified.

17. The method of operating an electron discharge device having an electron emitting cathode, an anode and two grid electrodes interposed between cathode and anode to amplify a variable electric current which consists in maintaining the anode and grid electrode nearest the anode at such potentials with respect to the cathode that the device will have a negative resistance characteristic between cathode and said grid electrode, and supplying the current to be amplified to a circuit between the cathode and the grid electrode nearest the cathode and thereby varying the current flow between cathode and anode in accordance with the current to be amplified.

In witness whereof, I have hereunto set my hand this 17th day of December, 1920.

ALBERT W. HULL.

Certificate of Correction.

It is hereby certified that in Letters Patent No. 1,610,783, granted December 14, 1926, upon the application of Albert W. Hull, of Schenectady, New York, for an improvement in "Electron-Discharge Apparatus," an error appears in the printed specification requiring correction as follows: Page 2, line 76, claim 2, after the word "discharge" insert the word *device*; and that the said Letters Patent should be read with this correction therein that the same may conform to the record of the case in the Patent Office.

Signed and sealed this 1st day of February, A. D. 1927.

[SEAL.]

M. J. MOORE,
Acting Commissioner of Patents.
